UNITED STATES PATENT OFFICE.

EDGAR H. CLARK, OF RICHMOND HILL, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed May 19, 1920. Serial No. 382,502.

To all whom it may concern:

Be it known that I, EDGAR H. CLARK, a citizen of the United States, residing at Richmond Hill, in the county of Queens, 5 State of New York, have invented certain new and useful Improvements in Telephone-Exchange Systems, of which the following is a full, clear, concise, and exact description.

10 This invention relates to telephone exchange systems involving a plurality of offices and particularly to systems in which inter-office connections are established in part by the use of machine switching apparatus.

15 The object of the invention is the provision, in telephone systems where operators are employed for manually extending connections over trunks leading to succeeding 20 switching devices, of means for indicating to the operator the identity of an automatically selected trunk to be used by her in extending such connections.

25 A feature of the invention relates to an arrangement; in systems of this character where the trunks at an operator's position are divided into groups, with progressively operable switching devices, one for each group, for automatically selecting an idle 30 trunk from any group; in which the extent of operation of a progressively operable indicator selecting mechanism is determined by the particular switching device taken 35 for use to indicate to the operator the designation of the group containing the selected trunk and also the location of the trunk in such group.

40 Another feature relates to the provision of a plurality of trunk selecting switches, one for each group of trunks, arranged to be 45 serially operated to select a group containing an idle trunk and to select the idle trunk in such group, and indicator selecting switches arranged to be progressively operated in 50 accordance with the particular trunk selecting switch taken for use and also in accordance with the extent of operation of said particular switch for indicating to the operator the designation of the selected idle

55 Other features contemplated by the invention will become more apparent from a consideration of the following description and appended claims.

Referring to the drawing which constitutes a part of the disclosure, Figs. 1 to 5 inclusive, when arranged in the order shown in Fig. 6, illustrates so much of a telephone system embodying this invention as is necessary to a comprehensive understanding 60 thereof. Fig. 1 shows an operator's position in a manual office provided with cord circuits for extending subscribers' lines over interoffice trunk lines outgoing to distant mechanical offices. Fig. 2 and 3 show two 65 of a series of trunk selecting switches for automatically selecting an idle trunk outgoing from the operator's position to the desired mechanical office. Fig. 4 shows, on the right, a sender selector switch for associating an idle sending mechanism with the selected outgoing trunk, and on the left, an operator's position switch for associating the equipment at the calling operator's 70 position with the selected outgoing trunk 75 and with the selected sending mechanism. Fig. 5 illustrates the controlling and indicating equipment at the operator's position.

80 In the system disclosed, connections are established by the operators in a manual originating office to any of a plurality of distant mechanical offices. For each mechanical office to which the operators in the manual office have access, there is provided a group of interconnecting trunk lines terminating in machine switches at the mechanical office. These groups of trunks are multiplied so as to appear in calling jacks at each of the manual operators' positions. The operator responds, in the usual manner, to the initiation of a call on a subscriber's line which terminates at her position. Ascertaining the name of the called 85 office and the number of the wanted line in that office, she manipulates the necessary apparatus at her position, which causes the automatic selection of an idle trunk outgoing to the called office, the association of an idle sending mechanism with her position and the visual indication of the designation 90 of the selected trunk. She then sets up the number of the called line on a keyboard at her position and completes the connection by inserting the calling plug of her cord circuit in the jack of the selected outgoing 100 trunk. The manipulation of the keyboard causes the desired designation to be registered on the sending mechanism which 105

thereupon serves to control, over the selected trunk, the operation of the selective switches in the called mechanical office.

A plurality of selecting units are assigned 5 to each group of interoffice trunks leading to distant mechanical offices, one of which offices is represented at 120 in Fig. 1. One of these selecting units consists of a plurality of step-by-step trunk selecting 10 switches such as 200 and 300, a step-by-step sender selecting switch 420, and a step-by-step operator's position switch 400. Where the traffic between the manual office and the 15 mechanical office 120 is comparatively heavy, a large group of interoffice trunks is necessary. Inasmuch as the small step-by-step trunk selecting switches 200 and 300 only have a capacity of 20 trunks, it is necessary to provide a plurality of these 20 switches for the entire group of outgoing trunks. Assuming that the outgoing trunk group contains 160 trunks, eight trunk selecting switches are provided, each having access to a group of 20 trunks, with means 25 for successively operating the switches to select an idle trunk for use by the operator. The sender selecting switch 420 of the switching unit has access to a plurality of sending mechanisms common to all the operators in the manual office. The operator's 30 selecting switch 400, which, together with the sender selector 420 and the series of eight trunk selectors, comprises one selecting unit, operates automatically in response 35 to the initiation of a call to select the operator's position at which such call was initiated. An allotter 410 is provided for the plurality of switching units assigned to an outgoing trunk group. The 40 function of this allotter is to keep an idle switching unit constantly allotted for use by any of the manual operators who wishes to extend a connection to the corresponding mechanical office.

45 At each operator's position a plurality of office keys, such as 500, are provided, one for each distant mechanical office to which the operator has access. The depression of the office key 500, individual to any mechanical office, initiates the simultaneous operation of the selecting switches of the allotted switching unit individual to the group of trunks leading to such mechanical office. Any one of the eight trunk selecting 50 switches, such as 200, 300, may be the first to be set in operation, dependent upon the group of 20 trunks in which an idle trunk was taken for use in the last preceding connection. This switch hunts automatically 55 and if no idle trunk is found in its group of 20, returns to normal position and initiates the hunting operation of the next succeeding selecting switch in the series. The next switch hunts over its group of 20 trunks and so on until one of the group of 60

eight switches finds an idle trunk. A side switch designated at 320 is provided for each group of eight trunk selecting switches and serves to control the operating circuits during the change-over from one switch to another.

In addition to the equipment thus far described, the operator's position is also provided with a plurality of number indicating lamps for displaying before the operator the hundreds, tens and units designations of the automatically selected outgoing trunk. Since the trunk group is said to contain 160 trunks, only two hundreds lamps, the No. 0 and the No. 1 lamps are required. A stepping switch 510 having ten positions is arranged to select the tens lamp identifying the number of the tens group in either hundred in which the selected idle trunk is contained. A second stepping 85 switch 520 is arranged to select one of ten units lamps to indicate the units location of the selected trunk in the group of ten. As will be explained more fully hereinafter, these lamp selecting switches are set in operation following the completion of the trunk selecting operation and are governed in the extent of their motion by the position in which the side switch 320 is standing and also by the position assumed by the particular trunk selecting switch in selecting the idle trunk.

The operator's position is further provided with a single row of ten non-locking keys 515. By depressing the proper combination of these keys, the designation of the called line is registered on the sending mechanism selected by the switch 420. It is not considered necessary to show and describe the sending mechanism since the same does not specifically concern the subject matter of the present invention. Any sending mechanism suitable for controlling power driven switches of the reverte impulse type may be employed. A sender of the specific type shown and described in detail in the British patent to Western Electric Company, Incorporated, No. 173,009, accepted December 12, 1921, may be utilized in this system. Having given a general outline of the system, a detailed description of the operations involved in the establishment of a connection will now be taken up.

Assume that the subscriber at substation 100, whose line terminates in the manual office, wishes to converse with the subscriber at substation 130, whose line terminates in the mechanical switching office 120. The calling subscriber by removing his receiver from the switch hook completes a circuit from battery, through the left-hand winding of relay 103, outer armature and contact of cut-off relay 105, over the line and substation circuit, returning through the contact and inner armature of relay 105 and 130

the right-hand winding of relay 103 to ground. Relay 103 becomes energized and closes a circuit for the illumination of the calling line lamp 104. The operator, observing the calling signal 104 answers by inserting the plug 102 of an idle cord circuit in the jack 101 of the calling line. A circuit is thereupon completed from battery, through the supervisory lamp 106, resistance 115, sleeve of plug 102, sleeve of jack 101, winding of relay 105 to ground. Relay 105 opens the circuit of the line relay 102, which, in turn, deenergizes. At the same time a circuit is closed from battery, through the lower left-hand winding of repeating coil 109, winding of supervisory relay 107, ring of plug 102, ring of jack 101, over the calling line circuit, tip of jack 101, tip of plug 102, upper left-hand winding of repeating coil 109 to ground. Relay 107 becomes energized and completes a circuit from battery, through the contact and armature of relay 107, resistances 116 and 115 to ground through the winding of relay 105. Relay 105 remains energized in this circuit and supervisory lamp 106, being shunted, is not illuminated. The operator depresses her listening key 117, which connects her telephone set 118 in talking relation with the calling line. She then communicates with the calling subscriber and receives the name of the wanted office and the numerical designation of the desired line in that office. Having received this information the operator releases her listening key 117 and depresses the office key 500 at her position corresponding to the name of the called mechanical office 120.

In response to the depression of key 500 a circuit is completed from battery, through the armature and contact of relay 503, right-hand windings of relays 502 and 501, left-hand contact of key 500 to ground at the right-hand armature and contact of relay 505. Relays 501 and 502 are energized and a holding circuit is established therefor independently of key 500. This circuit may be traced from battery, through the armature and contact of relay 503, left-hand windings of relays 502 and 501, contact 516, attracted right-hand armature of relay 501, winding of relay 504, contact and inner right-hand armature of relay 508 to ground. Relay 504 also becomes energized in this circuit. The actuation of key 500 closes another circuit traceable from battery, through the winding of relay 506, back contact and left-hand armature of relay 505, right-hand contact of key 500 to ground. Relay 506 energizes and closes a circuit from battery, through relay 506 and relay 505 in series, contact and armature of relay 506 to ground at the contact and right-hand armature of relay 502. Relay 505, does not become energized, however, until key 500 is released to remove the shunt from around the winding thereof closed at the right-hand contact of said key. This insures that relays 501 and 502 have sufficient time to energize and lock up before their original operating circuit is opened at the right-hand armature of relay 505. The energization of relay 501 completes a starting circuit for initiating the operation of the switches comprising the allotted switching unit. The starting circuit may be traced from ground, through the left-hand closed contacts of relay 504, outer left-hand armature and contact of relay 501, conductor 517, lower right-hand winding of balancing coil 415, winding of polarized relay 416, upper left-hand winding of coil 415, to battery and ground. A parallel path leads through the lower windings of coil 415 to battery. Current flowing in this direction through the windings of coil 415, serves to unbalance the same whereby the polarized relay 416 attracts its armature. A circuit is then closed from ground, contact and armature of relay 416, armature and contact of relay 413, brush 411 of allotter 410, through the left-hand winding of relay 408, individual to the allotted switching unit, right-hand winding of relay 409 to battery and ground. Relay 408 becomes energized and closes a locking circuit for itself from battery, through the right-hand winding, contact and inner right-hand armature of said relay to ground at the contact and upper armature of relay 428. Relay 409 also completes a holding circuit for itself from battery, through the left-hand winding and inner right-hand contacts and armature of said relay to ground at the contact and lower armature of relay 428. Relay 408 establishes a circuit from battery, through the winding of relay 417, contact and uppermost armature of relay 434, contact and innermost right-hand armature of relay 408, contact and upper armature of relay 428 to ground. Relay 417 closes a circuit from battery, through the winding of stepping magnet 407 of the operator's position selecting switch, armature and contact of said magnet, outer left-hand armature and contact of relay 417, winding of relay 418, inner left-hand armature and contact of relay 417 to ground. Provided the hunting brush 401 of the operator's position switch is standing on the terminal representing a non-calling operator's position, relay 418 remains deenergized by means of the following circuit closed directly to ground in shunt of the winding of said relay: battery through the winding and armature and contact of magnet 407, outer left-hand armature and contact of relay 417, back contact and armature of relay 418, hunting brush 401, conductor 518, to ground at the contact 516 of relay 501 at the non-calling operator's position. Relay 418 therefore remains deenergized and

the stepping magnet 407 interrupts its own circuit and advances the brushes 401 to 406 inclusive to the next position terminals. The operator's position switch continues to advance in this manner, passing over the terminals representing non-calling operator's positions, and finally reaches the terminals individual to the operator's position at which key 500 was depressed. Since relay 501, at 10 this position, is energized, the stepping circuit of magnet 407 is no longer connected directly to ground at contact 516 but now leads through the actuated contact 516 and attracted right-hand armature of relay 501 15 to the winding of relay 504 and thence to ground at the contact and inner right-hand armature of relay 508. The stepping magnet 407 ceases to operate in view of the fact that this circuit includes the comparatively 20 high resistance of relay 504. The left-hand windings of relays 502 and 501 are shunted out at this point due to the application of battery current at the contact 516 of relay 501. These relays, however, remain energized in a circuit completed from battery, through the armature and contact of relay 503, right-hand windings of relay 502 and 501, inner left-hand armature and contact of 25 relay 501 to ground at the left-hand armature and contact of relay 504. Due to the comparatively high resistance of relay 504 at the operator's position, the flow of current is sufficiently increased in the circuit above traced for causing the energization of relay 30 418. Relay 418 therefore energizes in series with magnet 407, but due to its resistance, said relay prevents the further operation of the stepping magnet. The brushes of the operator's position switch are, therefore, 35 brought to rest. The operation of relay 418 opens the circuit traced, for the application of battery current through the winding of magnet 407 and thence to the contact 516 of relay 501. Relay 418 furthermore completes 40 a circuit from battery, through the armature and contact of relay 503, left-hand windings of relays 502 and 501, actuated contact 516, conductor 518, brush 401, armature and front contact of relay 418, winding of relay 45 509 to ground. The resistance of relay 419 is such that a sufficient amount of current is shunted away from the winding of relay 504 to permit this latter relay to release its armatures. Relays 502, 501 and 419 now remain 55 energized in series with each other. Should the hunting brush 401 of another switching unit, individual to the called mechanical office, encounter the terminals individual to the busy operator's position, the stepping magnet 407 of such other switching unit would 60 continue to operate in a circuit closed over the multiple terminals of the hunting brush 401, through the armature and front contact of relay 418 and the winding of relay 419 of 65 the switching unit shown. Relay 419 on en-

ergizing completes the following holding circuit for itself and relays 502 and 501 independently of the armature and front contact of relay 418: battery, through the armature and contact of relay 503, left-hand windings 70 of relays 502 and 501, contact 516, conductor 518, brush 401, left-hand armature and contact of relay 408, left-hand armature and contact and winding of relay 419 to ground: Relay 419, also establishes a circuit from battery, through the winding of relay 432, contact and right-hand armature of relay 419 to ground. 75

Returning now to the point where relay 408 and consequently, relay 417 of the allotted switching unit were first energized, a description will be given of the allotment of the next idle switching unit for use in connection with a subsequent call. When relay 417 is energized, a circuit is established from battery, through the lower left-hand winding of coil 415, winding of polarized relay 416, upper right-hand winding of coil 415, contact and right-hand armature of relay 417, back contact and right-hand armature of 80 relay 432 to ground. A parallel branch leads through the upper windings of coil 415. Current flowing in this direction through the windings of coil 415 serves to balance the same, thereby causing the polarized relay 416 to retract its armature. The energization of relay 409, which takes place simultaneously with the operation of relay 408, causes a circuit to be closed from battery, through the winding and contact and armature of the allotter stepping magnet 85 414, brush 412, contact and outermost left-hand armature of relay 409 to ground. The stepping magnet 414 energizes, interrupts its own circuit and advances the brushes 411 and 412 into engagement with the terminals individual to the next succeeding switching unit in the group. If this next unit is busy, the relay 409 thereof is energized and a circuit is closed for the continued operation of 90 magnet 414. The allotter switch continues to step, therefore, until the first idle switching unit in the group is found, at which time the stepping circuit is opened and the brushes 411 and 412 are brought to rest. 95 During the operation of the stepping magnet 414, the slow to release relay 413 is maintained energized. This relay, at its armature and contact holds open the starting circuit hereinbefore traced, through the brush 411 and the windings of relays 408 and 409 so that if any operator unbalances the coil 100 415 by depressing an office key corresponding to key 500, during the time the allotter switch is searching for an idle switching unit, the start circuit will not be completed. After the stepping magnet 414 ceases to operate, following the selection of an idle switching unit, the slow to release relay 105 413 becomes deenergized and closes the 110 115 120 125 130

break point in the start circuit whereby this circuit may be completed at the armature and contact of the polarized relay 416, when the coil 415 is unbalanced by the key 500 at 5 another calling operator's position and the allotted switching unit taken for use.

When the relay 409 becomes energized an operating circuit is closed for the stepping magnet 427 of the selecting switch 420. This 10 circuit may be traced from battery, through the winding and armature and contact of magnet 427, back contact and right-hand armature of relay 430, contact and outer right-hand armature of relay 409 to the test brush 426. If the brush 426 is standing on a terminal individual to a busy sending mechanism, a ground will be present on such terminal and magnet 427 becomes energized. The magnet 427 interrupts its own circuit 15 and causes the advance of the brushes 421 to 426 inclusive to the next succeeding position. The test brush 426 engages a grounded terminal for each succeeding busy sending mechanism and the switch continues 20 to operate under the control of magnet 427. During the operation of the sender selecting switch 420, a circuit is maintained as follows for the relay 430: battery, through the winding and armature and contact of magnet 427, winding of relay 430, contact and inner right-hand armature of relay 409, contact and lower armature of relay 428 to ground. Relay 430 remains deenergized, 25 however, due to the shunt circuit closed directly to ground at the terminals of busy sending mechanisms encountered at the test brush 426. When brush 426 engages an ungrounded terminal, identifying an idle sending mechanism, the shunt is removed from 30 around the relay 430 and this relay attracts its armatures. The resistance of relay 430 now being included in series with the stepping magnet 427, such magnet does not receive sufficient current to continue its operation 35 and the brushes of the switch 420 are consequently brought to rest. When the test brush 426 encounters the terminal individual to an idle sending mechanism, a battery potential is supplied from such mechanism 40 over the test brush 426 and thence through the outer left-hand armature and contact of relay 409, right-hand armature and front contact of relay 430, winding of relay 431 to ground. The manner in which busy sending 45 mechanisms furnish ground potential, and idle mechanisms furnish battery potential at the terminals cooperating with the test brush 426, is shown and described in detail in the British Patent No. 173,009, accepted 50 December 12, 1921. Relay 431 attracts its armatures and provides a substitute holding ground for relay 409 for a purpose to be hereinafter explained. Relay 430, at the 55 time of its energization, also establishes a circuit from battery, through the winding

of relay 434, inner left-hand armature and contact of relay 430, front contact and right-hand armature of relay 432 to ground. Relay 434 energizes in this circuit and attracts 60 its armatures.

At the same time that relays 408 and 409 initiate the operation of the operator's position switch 400 and the sender selecting switch 420, a circuit is also completed for the operation of the trunk selecting 65 switches. It will be assumed that each of the series of eight trunk selecting switches, 300, 200, and so forth, is in its normal position. As shown in Figs. 2 and 3, the brushes of the trunk selecting switches when 70 in their normal positions are standing on the No. 21 contacts. That is to say, the trunk selecting switches are each provided with twenty-two positions, the first twenty 75 of which are assigned to the corresponding group of twenty trunks and the remaining two positions are used for change-over operations as will presently appear. When, therefore, the relay 409 first attracts its 80 armatures, an operating circuit is completed 85 as follows for the stepping magnet 307 of the first trunk selecting switch, 300, in the series: battery, through the winding of magnet 307, armature and contact of said magnet, first position terminal and brush 324. 90 of side switch 320, conductor 334, contact and innermost left-hand armature of relay 409, conductor 335, back contact and inner left-hand armature of relay 308, brush 322 and its first position terminal, conductor 336, test brush 302 of trunk selector 300 and its No. 21 contact to ground. Magnet 307 is energized, interrupts its own circuit 95 and advances the brushes 301, 302, 303, 100 304, 305 and 306 respectively into engagement with their No. 0 contacts, which represents the No. 0 or first trunk in the first 105 group of twenty trunks outgoing from the manual office to the called mechanical office 120. If this first trunk is busy, the brush 302 finds a ground potential on the test terminal thereof and stepping magnet 307 again energizes to advance the selector brushes onto the next set of terminals representing the No. 1 trunk in the first group. During the operation of the trunk selecting switch in testing the condition of the outgoing trunks, a parallel circuit is maintained 110 as follows through the winding of relay 308: battery, through the winding and armature and contact of magnet 307, brush 324, conductor 334, innermost armature and contact of relay 409, conductor 335, winding of relay 308, back contact and armature of relay 328, conductor 337, contact and outermost left-hand armature of relay 409 to ground. Relay 308, however, being 115 shunted out by the direct circuit to ground at test brush 302 does not operate as long 120 as busy trunks are encountered. Assume 125 as busy trunks are encountered. Assume 130

that the first half of the first group of twenty trunks, namely trunks No. 0 to No. 9, are busy. The brushes of the selecting switch 300 are, therefore, advanced to their No. 10 position terminals, which represent the first trunk in the second half of the group twenty. In this position, the brush 301 engages the grounded terminal 338 and a circuit is closed from battery through the 10 winding of magnet 327, armature and contact of said magnet, brush 321 and its first position terminal, conductor 339, brush 301, and terminal 338 to ground. The magnet 327 energizes, interrupts its own circuit and 15 advances the brushes 321, 322, 323, 324, 325 and 326 of the side switch to their second position terminals. If the first or No. 0 trunk in the second half of the first group of twenty trunks is busy, the stepping magnet 307 is energized as before, the only difference being that the operating circuit therefor now leads through the second position terminals of side switch brushes 324 and 322.

25 Assuming that all of the second group of trunks appearing in the switch 300 are busy, the brushes continue to advance until they reach their No. 20 position terminals. In this position a circuit is established as 30 follows: battery, through the winding and armature and contact of stepping magnet 307, brush 324 and its second position terminal, conductor 334, contact and inner left-hand armature of relay 409, conductor 335, back contact and inner left-hand armature of relay 308, brush 322 and its third position terminal, conductor 336, brush 302 and its No. 20 position terminal 340, conductor 341, and winding of relay 328 to 35 ground. Relay 328 becomes energized, but due to the resistance of this relay, stepping magnet 307 does not receive sufficient current to operate. Relay 328 at its armature and back contact opens the hereinbefore 40 traced circuit for relay 308 to prevent such relay from energizing at this time. Relay 328 also closes a circuit from battery, through the winding of the side switch stepping magnet 327, front contact and armature of relay 328, conductor 337, contact and outermost left-hand armature of relay 409 to ground. Magnet 327 completes a circuit from ground through its left-hand armature and contact, brush 323 and its 45 second position terminal, conductor 342, winding of stepping magnet 307 to battery and ground. Stepping magnets 307 and 327, are therefore simultaneously energized. Magnet 307, by attracting its armature, opens the above traced circuit for relay 328. Relay 328, in turn, opens the energizing circuit of stepping magnet 327. Magnet 327 deenergizes and causes the brushes of the side switch to be advanced to their 50 60 65 third position terminals. It may be well to

observe, at this point, that the stepping switches disclosed in this system are designed to step their brushes forward on deenergization of the operating magnets. As soon as the side switch leaves its second position the circuit of magnet 307 is opened at brush 323. The magnet 307 thereupon becomes deenergized and advances the brushes of the switch 300 onto their No. 21 position terminals. 70 75

By the time the stepping magnet 327 closes its armature and contact, following the deenergization of relay 328, the brushes of selecting switch 300 have advanced to their No. 21 position terminals. Relay 308, 80 therefore, does not energize in series with stepping magnet 307. The first trunk selecting switch 300 has now been restored to its normal position and an operating circuit is immediately established to start the hunting operation of the second selecting switch 200 which has access to the second group of twenty outgoing trunks. This operating circuit may be traced from battery, through the winding and armature and contact of magnet 207 of the switch 200, conductor 210, brush 324 and its third position terminal, conductor 334, contact and innermost left-hand armature of relay 409, conductor 335, back contact and inner left-hand armature of relay 308, brush 322 and its third position terminal, conductor 211, test brush 202 and its No. 21 position terminal to ground. A parallel circuit is also established for relay 308 from battery, through the winding and armature and contact of magnet 207, conductor 210, brush 324 and thence, as described, to conductor 335, winding of relay 308, back contact and armature of relay 328, conductor 337, to ground at the outermost armature and contact of relay 409. Relay 308, however, remains deenergized so long as its winding is shunted out by a direct circuit to ground at the brush 202 and busy test terminals. 90 95 100 105 110

Assume that the No. 9 trunk, in the first half of the second group of twenty, served by the selecting switch 200, is the first idle trunk to be encountered. Hence the stepping magnet 207 continues to advance the brushes 201, 202, 203, 204, 205 and 206 until they reach the terminals corresponding to the idle trunk. No ground being present on the test terminal of this trunk, the shunt which has heretofore been maintained around the winding of relay 308, is now removed and this relay energizes in series with the stepping magnet 207. Magnet 207 ceases to operate by reason of the resistance of relay 308 included in its circuit. It will thus be seen that the idle trunk selected is the No. 9 trunk in the first ten trunks of the second group of twenty. Therefore, the number of this trunk is 29 and since it belongs to the first hundreds group, its complete designa- 115 120 125 130

tion is 029. It will also be observed that the side switch 320 has taken one step for each group of ten trunks hunted over and is consequently standing in its third position 5 responding to the third group of ten trunks in which the selected trunk appears. Moreover, the brush 206 of the trunk selecting switch 200 is standing on its No. 9 position terminal 212, which corresponds to the units 10 location of the selected trunk in the first group of ten trunks served by the switch 200. The side switch and the trunk selecting switch in assuming these positions corresponding to the tens and units location of 15 the selected trunk later perform certain functions, as will presently be described, in determining the visual indication of the designation to identify to the operator the number of the selected trunk.

20 When relay 308 becomes energized a circuit is closed from ground, through the front contact and inner left-hand armature of said relay, side switch brush 322 in its third position, conductor 211, test brush 202 25 and thence to the multiple terminals of the selected trunk in all other trunk selecting switches of the group of selecting units having access to trunks leading to the mechanical office 120. In this manner, the selected 30 trunk is rendered busy to other selecting units. Relay 308 also closes a circuit from ground through its contact and outer left-hand armature, conductor 343, front contact and inner left-hand armature of relay 432, 35 winding of relay 435, to battery and ground. Relay 435 completes a circuit from ground through its middle lower armature and contact, conductor 436, right-hand armature and contact of relay 431, contact 437, winding 40 of relay 433 to battery and ground. Relay 433 attracts its armature and closes a holding circuit for itself from battery, through its winding, contact 437, inner left-hand armature of said relay to ground at the 45 contact and outer left-hand armature of relay 409. Relay 433 also completes a circuit from battery, through the upper winding of relay 428, contact and innermost right-hand armature of relay 433, conductor 345, brush 50 303, and its normal position terminal, conductor 346, brush 203, terminal 213, conductor 214, through the windings of relay 114 to ground. Relay 114 attracts its armatures but due to its left-hand high resistance winding the marginal relay 428 is not able to 55 energize.

The manipulation of the operator's keyboard 515 for the purpose of registering the called line designation on the selected sending mechanism, will be considered before proceeding to describe the operation involved in indicating the designation of the selected idle trunk. After the operator has received the office and numerical designation 60 from the calling subscriber and has actuated the proper office key 500, she then proceeds, after an interval, to set up the desired number by depressing in succession the proper keys on her keyboard 515. As fully explained in the above mentioned British 70 Patent No. 173,009, accepted December 12, 1921, the depression of these keys causes the designation to be recorded on the relay registers of the sending mechanism which later serves to control the selecting operation of 75 the switches 121 and 122 in the distant mechanical office to extend the connection to the called subscriber's line. Should the operator attempt to set up the designation on her keyboard prior to the time that the operator's position switch 400 had found her position, or should all of the link circuits individual to the office 120 be engaged, a signal to that effect is given the operator. 80 When any of the keys on her keyboard 515 is 85 depressed under these circumstances, a circuit is completed from battery, through the winding of relay 523, front contact and right-hand armature of relay 504, contact and outer right-hand armature of relay 508, 90 conductor 524, to ground either through resistance 525 or 526 or one of the windings of relay 527 dependent upon the particular key operated. Relay 523 completes a circuit for the illumination of lamp 530 which 95 informs the operator that a link circuit has not yet been assigned to her for use.

If all of the sending mechanisms are 100 found busy by the selecting switch 420, and consequently no sending mechanism is assigned to the calling operator, she is advised of this fact as soon as she depresses one of the keys on her keyboard 515. By the depression of any of the keys on keyboard 515, 105 a circuit is closed, in this case, from battery, through the winding of relay 531, back contact and right-hand armature of relay 504, contact and outer right-hand armature of relay 508 to ground through resistance 525, 110 resistance 526, or either of the windings of relay 527 according to the key operated. This circuit leads through the back contact and armature of relay 504, which relay it will be remembered becomes deenergized as 115 soon as the operator's position switch finds the calling position. Relay 531 attracts its armature and completes a circuit from the tone coil 533, contact and right-hand armature of relay 531, conductor 532 and thence to ground through the tertiary winding of 120 the operator's telephone set 118 shown in Fig. 1. This tone advises the operator that all the sending mechanisms are busy.

When an idle switching unit is allotted for 125 use by the calling operator and the selecting switch 420 finds an idle sending mechanism, relay 434 in Fig. 4, energizes in the manner already explained. Relay 434 completes a circuit from ground, through the right-hand armature and contact of relay 502, winding 130

of relay 507, back contact and armature of relay 508, conductor 534, brush 404, inner upper armature and contact of relay 434, conductor 438, brush 423 and thence to battery at the selected sending mechanism as disclosed in the above mentioned British Patent No. 173,009, accepted December 12, 1921. Relay 507 becomes energized in this circuit and closes a circuit for itself from battery, through its armature and contacts and winding to ground at the contact and right-hand armature of relay 502. Relay 507 also completes a circuit from battery, through its armature and contact; and winding of relay 508 to ground. Relay 508 becomes energized whereby the following actuation of a key on the operator's keyboard is ineffective to cause the illumination of lamp 530 or to produce a tone in the operator's receiver. The operator's keyboard is now connected over conductors 524, 534, 535 and 536, brushes 404, 405, and 406, the corresponding armatures and front contacts of relay 434, conductors 438, 439 and 440, brushes 423, 424 and 425 of switch 420 and thence to the selected sending mechanism. The operator may thereupon proceed to register the called line designation on the registers of the sending mechanism.

30 After the called line designation has been set up on the sending mechanism, the usual fundamental impulse controlling circuit is established over brushes 421 and 422, contacts and outer right-hand armatures of relay 433, brushes 305 and 304, conductors 347 and 348, brushes 205 and 204, conductors 215 and 216, front contacts and armatures of relay 114 and thence over conductors 131 and 132 to the first switch 121 in the mechanical office. In the manner fully described in the above mentioned application, the switches 121 and 122 are positioned under the control of the sending mechanism in accordance with the called line designation registered thereon.

50 A consideration will next be given of the mechanism employed for visually indicating to the operator the designation of the automatically selected trunk in order that she may know which one of the entire group of trunks to use in extending the connection. For this purpose two step-by-step switches 350 and 360, the brushes of which are respectively designated 314 and 315 in Fig. 3, are provided. Each of the ten terminals cooperating with brush 314 is connected, as shown, to the corresponding terminal in the first group of ten terminals of the side switch bank cooperating with brush 326 and also to the corresponding terminal in the second group of ten terminals in said bank. In other words, terminal No. 0 of switch 350 is connected to terminal No. 0 in both the first and second groups of ten terminals in the side switch bank. Terminal No. 1 of

switch 350 is connected to terminal No. 1 of both the first and second groups in the terminal bank of the side switch, and so on. Each of the ten terminals of the second stepping switch 360 with which the brush 315 70 cooperates is connected to the correspondingly numbered terminal in both the first and second group of ten terminals in one of the banks of each of the eight trunk selecting switches. The multiple connections between the terminals of switch 360 and the terminals of the banks cooperating with brushes 306 and 206 of the first two trunk selecting switches are shown in the drawing. The same method of multiplying these connections is employed throughout the entire series of trunk selecting switches.

It will be recalled that the relay 308 was energized in response to the selection of an idle trunk by the trunk selecting switch 200. 85 The relay 308 in addition to completing the circuit for relay 435 and rendering the selected trunk busy as above explained, closes a circuit from battery, through the winding of relay 309, contact and right-hand armature of relay 308, conductor 363, to ground at the outer left-hand armature and contact of relay 432. Relay 309 becomes energized and closes a circuit from ground, through its outer left-hand armature and contact, contact and armature of relay 310, contact and armature and winding of stepping magnet 312, interrupter 332 to battery and ground. Relay 309 further completes a circuit from ground, through its inner left-hand armature and contact, contact and armature of relay 311, contact and armature and winding of stepping magnet 313, and interrupter 333 to battery and ground. The stepping magnet 312 which operates the stepping switch 350 is energized and deenergized in response to the first closure and opening of the interrupter 332 and advances the brush 314 into engagement with its first or No. 0 terminal. In this manner, the brush 314 is advanced 100 from one terminal to the next until it reaches the third or No. 2 terminal 352. In this position, a circuit is immediately closed from battery through the inner right-hand armature and contact of relay 309, winding of relay 310, brush 314, terminal 352, terminal 353, on which the side switch brush 326 is standing, brush 326, brush 325 and its third position terminal to ground. Relay 310 energizes and opens the operating circuit of magnet 312 whereby the brush 314 ceases to advance. For each energization of stepping magnet 312 as the brush 314 is stepping forward in search of a grounded terminal which represents the numerical designation of the group of trunks containing the selected trunk, a circuit is completed from ground, through the right-hand armature and contact of magnet 312, conductor 354, contact and upper armature of relay 435, brush 402,

110

115

120

125

130

conductor 537, winding of stepping magnet 511 to battery and ground. In response to the repeated closure of this circuit, magnet 511 steps the brush 510 to its third position 5 terminal 538.

Simultaneously with the operation of magnet 312, the stepping magnet 313 of switch 360 is also operated by the interrupter 333 and advances the brush 315 over its 10 successive terminals in search of a grounded terminal. The brush 315 continues to move until it reaches its No. 9 terminal 355. A circuit is then closed from battery, through the outer right-hand armature and contact 15 of relay 309, winding of relay 311, brush 315, terminal 355, multiple conductor 356, terminal 212, and brush 206 of switch 200 to ground. Relay 311 energizes and opens the operating circuit of magnet 313, causing 20 the brush 315 to discontinue its forward movement. For each operation of the stepping magnet 313 as the brush 315 steps forward to its No. 9 terminal 355, which corresponds to the units location of the selected 25 trunk in the third group of ten trunks, a circuit is closed from ground, through the left-hand armature and contact of relay 313, conductor 358, contact and innermost lower armature of relay 435, brush 403, conductor 30 539, winding of stepping magnet 521 to battery and ground. In response to the closure of this circuit, stepping magnet 521 operates and advances the brush 520 through ten steps into engagement with its No. 9 terminal 35 540. On the first energization of the stepping magnet 521, a circuit is closed from battery, through the winding of relay 509 to ground at the contact and left-hand armature of magnet 521. Relay 509 energizes 40 and closes a holding circuit for itself traceable from battery, through the winding and contact and inner right-hand armature of said relay, conductor 541, to ground at the innermost left-hand armature and contact 45 of relay 502.

The relay 509 completes the circuits for illumination of the proper hundreds, tens and units lamps which indicate to the operator the designation of the selected trunk 50 outgoing to the mechanical office 120. The circuit for the hundreds lamp 542 may be traced from battery, through said lamp, back contact and outer right-hand armature of relay 513, contact and inner left-hand armature of relay 509 to ground. The circuit of the No. 55 545 tens lamp leads from battery, through said lamp, terminal 538, brush 510, contact and outer left-hand armature of relay 509 to ground. The circuit of the No. 9 units lamp 544 leads from battery, through said lamp, terminal 540, brush 520, to ground at the outer right-hand armature and contact of relay 509.

The operator, observing the illumination 60 65 of the indicator lamps, seizes the plug 110

of her cord circuit and inserts it in the jack 111 of the outgoing trunk, the number of which is 029. A circuit is thereupon established from battery, through the lamp 123, resistance 124, sleeve of plug 110, sleeve 70 of jack 111, winding of relay 112 to ground. Lamp 123 is illuminated and relay 112 becomes energized. Relay 112 completes a circuit from battery, through the winding of relay 113, contact and armature of relay 112, conductor 217, terminal 218, brush 202, conductor 211, brush 322, inner left-hand armature and front contact of relay 308 to ground. Relay 113 becomes energized and closes a holding circuit for itself as follows: 75 battery, through the winding of said relay, contact and armature of relay 112, to ground at the closed contacts at the right-hand armature of relay 113. At its right-hand armature and contact the relay 113 also shunts the high resistance winding of relay 114 from the circuit hereinbefore traced including the upper winding of marginal relay 428. Sufficient current now flows in this 80 circuit to permit the energization of the marginal relay 428 which operates to initiate the release of the equipment at the operator's position. Relay 428 at its upper armature and contact opens the holding circuit of relay 408 which in turn releases its armatures. 85 The retraction of the left-hand armature of relay 408 opens the series holding circuit of relays 419, 501 and 502. At its right-hand armature, relay 502 opens the holding 90 circuits of relays 505, 506 and 507. Relay 507 then causes the deenergization of relay 508. At its innermost left-hand armature, relay 502 opens the locking circuit of relay 509. Relay 502 also closes a circuit, from 95 battery, through the winding and contact and armature of stepping magnet 521, off-normal contact 522, which is closed during the time brush 520 is out of its normal position, to ground at the contact and middle left-hand armature of relay 502. Magnet 100 521 interrupts its own circuit and restores the brush 520 to its normal position. Relay 502 also completes a circuit from battery, through the winding and armature and contact of magnet 511, outermost left-hand 105 armature and contact of relay 502, off normal contact 512, which is closed during the time brush 510 is out of its normal position, to ground. Magnet 511 operates to step the brush 510 back to its normal position. The 110 apparatus at the operator's position is thus restored, ready to be taken for use in connection with subsequent calls.

The relay 419 of the switching unit, which 115 also releases at the time relay 408 is deenergized, opens the holding circuit of relay 432. Relay 432 becomes deenergized and opens the circuits of relays 435 and 434.

Relay 408 at its outermost right-hand 120 armature and back contact closes a circuit

including the off-normal contact 317 for the stepping magnet 313 of switch 360. Magnet 313 operates to restore the brush 315 to its normal position at which time 5 the off-normal contact 317 opens the circuit of said magnet and brings the switch to rest. At its middle right-hand armature, relay 408 closes a similar circuit including the off-normal contact 316 for the stepping magnet 312 of switch 350. Magnet 312 is successively energized by the interrupter 332 and restores the brush 314 to its normal position. Switches 350 and 360 having been restored, remain in their normal positions since 10 the operating circuits of magnets 312 and 313 are now opened at the armatures of relays 309, which relay was de-energized by the retraction of the outer left-hand armature of relay 432. As soon as relays 408 and 409 become 15 deenergized the selecting unit shown in the drawing may be allotted by the allotter 410 for further use. It may happen that the selecting unit disclosed is immediately allotted for use in connection with another 20 call while switches 350 and 360 are returning to their normal positions. This will make it possible for the selecting unit to be seized by another operator before the switches 350 and 360 have fully restored, in which case 25 the return of these switches might interfere with the transmission of the correct number of impulses to select the designation lamps at the second operator's position. It will be noted that the relay 419 deenergized 30 upon the deenergization of relay 408 and in so doing removes ground from the brush 401 which has been maintaining the operator's position non-selectable by other operator's position switches. Should another operator 35 seize the selecting unit shown and should the ground be removed from the brush 401, the operator's position switch 400 would immediately operate to find the second operator's position, all of which might occur before the switches 350 and 360 had restored. Therefore, to guard against this condition 40 the operator's switch 400 is caused to actuate continually, provided the unit is appropriated by another operator, and not to seize 45 that operator's position until the switches 350 and 360 are in condition to perform their functions when the trunk selecting switches have found an idle trunk.

The operator's position switch 400 is 50 caused to rotate continually by means of holding a ground potential on the test brush 401 after the relay 408 becomes deenergized. This potential may be applied from ground either at the off-normal contact 318 or the 55 off-normal contact 319 of the switches 350 and 360, respectively, conductor 359, thence to the brush 401. If at this time the coil 415 has been unbalanced and relay 417 operated, the circuit previously traced for 60 magnet 407 is established and leads through

the outer left contact of relay 417, left back contact of relay 418 to the grounded conductor 359. This ground is maintained on the conductor 359 to cause the continued operation of magnet 407 until both switches 350 and 360 have restored, whereby the off-normal contacts 318 and 319 are both opened. After the contacts 318 and 319 are opened 65 the switch 400 continues to rotate until it finds the operator's position in the manner previously explained.

As soon as the sending mechanism has completed its function of controlling the selecting operation of the switches 121 and 122, the battery potential, which, up to this time, has been maintaining the energization of relay 431 over the circuit including brush 426, is removed in the manner explained in the above mentioned British Patent No. 173,009, accepted December 12, 1921. Relay 431 becomes deenergized and opens the substitute locking circuit of relay 409. Relay 409 becomes deenergized since, as will be recalled, the original locking circuit therefor is opened at this time by the lower armature and contact of the marginal relay 428. Relay 499 on deenergizing, opens the series circuit through the winding of the stepping magnet 207 and relay 308. Relay 308 at its inner left-hand armature opens the original circuit for the application of busy ground potential on the test terminal 218 at the switch 200. A busy potential, however, is maintained as follows on the terminal 218 to render the trunk non-selectable until the connection has been broken down by the operator: ground, through the closed contacts at the right-hand armature of relay 113, conductor 217 and thence to the test terminal 218. Relay 409 opens the holding circuit of relay 433. The relay 433 in restraining its innermost right-hand armature opens the circuit which, up to this time, has been maintaining the energization of the marginal relay 428 in series with the low resistance winding of relay 114. Relays 428 and 114 therefore become deenergized. Relay 114 disconnects the trunk conductors 131 and 132 from the switch controlling conductors 215 and 216 and extends them to the right-hand windings of the repeating coil 109 in the operator's cord circuit.

When the called subscriber answers, the supervisory relay 108 in the operator's cord circuit is energized in the usual manner and completes a circuit from battery, through the contact and armature of said relay, resistance 133, resistance 124 to ground through the winding of relay 112. This circuit shunts out the lamp 123 thus informing the operator that the called subscriber has answered.

At the termination of the conversation, the calling and called subscribers, by replacing their receivers on the switch hooks,

cause the deenergization of relays 107 and 108 which, in turn, permit the illumination of the supervisory lamps 106 and 123. The operator then removes the plugs of her cord circuit from the jack 101 of the calling line, and jack 111 of the outgoing trunk circuit and relays 105 and 112 become deenergized. Relay 112, in turn, causes the deenergization of relay 113.

Should the sending mechanism complete its function of controlling the switches in the distant mechanical office prior to the time the operator inserts the plug 110 in jack 111 of the outgoing trunk, the relay 431 would become deenergized, as explained, in advance of the deenergization of relay 428. The deenergization of relay 431, in this case, is without effect, since the relay 409 depends for its release jointly upon the release of relay 431 and the energization of relay 428. As soon thereafter, as the operator inserts the plug in the jack, the relay 428 becomes deenergized as described, to in turn cause the release of relay 409 which brings about the results already explained.

It will next be assumed that all the trunks in the first hundred are busy when the trunk selecting switches perform their hunting operation. It will also be assumed that the first idle trunk to be found in the second hundred is trunk No. 129. The trunk selecting switches, therefore, operate in succession, one after another and the side switch 320 moves forward one step for each group of ten trunks hunted over. Since the selected idle trunk now resides in the first ten trunks of the seventh group of twenty, the side switch brush 326 is standing on its No. 2 position terminal 361 in the second half of the bank and brush 325 is standing on an open terminal. The units designation of the trunk being the same as in the case previously assumed the brush corresponding to brush 206 of the particular trunk selecting switch taken for use is in engagement with its No. 9 position terminal in the first half of the bank. When the side switch is standing in any one of its first ten positions, the off-normal contact 329 controlled thereby, is closed. A circuit is therefore completed from battery through the winding of relay 331, right-hand armature and contact of relay 330, contact 329, conductor 362 to ground at the contact and middle left-hand armature of relay 409. Relay 331 attracts its armature and closes a circuit for itself in series with relay 330 to ground as just described. Relay 330 does not energize, however, since its winding is shunted out by the direct circuit closed through the off-normal contact 329. When the side switch brush 326 leaves the last position in the first half of its bank, the contact 329 is opened and relay 330 ener-

gizes in series with relay 331. From here on, the operation of the system is the same as described, up to the point where relay 309 is energized and the switch 350 commences to operate under the control of its stepping magnet 312. Since the brush 326 is standing on terminal 361 in the second half of the bank, the brush 314 is driven through a complete cycle without finding a grounded terminal. Consequently the brush 510, which operates in synchronism with brush 314, makes a complete movement over its terminal bank. When brush 510 first leaves its normal position, contact 512 is closed and a circuit is established from battery, through the winding of relay 514, inner armature and contact of relay 513 to ground at the contact 512. Relay 514 attracts its armature and completes a circuit for itself in series with relay 513 to ground at the contact and innermost left-hand armature of relay 502. Relay 513 does not energize, however, since its winding is shunted out by the direct circuit closed to ground at off-normal contact 512. As soon as the brush 510 has taken ten steps and returns to its normal position, contact 512 is opened and relay 513 is energized in series with relay 514. The brush 314 of switch 350 continues to move through a second cycle. On reaching its No. 2 terminal 352, a circuit is completed from ground, through the contact and left-hand armature of relay 330, brush 326, terminal 361, terminal 352, brush 314, winding of relay 310, and inner right-hand armature and contact of relay 309 to battery and ground. Relay 310 energizes and causes the switch 350 to cease its rotation as hereinbefore described.

When the selection of the units lamp has been completed and relay 509 is energized, a circuit for the No. 1 hundreds lamp 545 is completed as follows: battery, through the lamp 545, front contact and outer armature of relay 513, to ground at the contact and inner left-hand armature of relay 509. The operator, observing the illumination of lamp 545 knows that trunk No. 29 in the No. 1 hundred has been selected for use.

What is claimed is:

1. In a telephone exchange system, an operator's position, a plurality of trunks arranged in groups at said position, trunk selecting devices, one for each group, means for operating said selecting devices to select a trunk in any of said groups, indicator selecting means, means controlled in accordance with which one of said trunk selecting devices is taken for use for determining the extent of operation of said indicator selecting means, indicator devices, and means controlled by said indicator selecting means for variably operating said indicator devices

to indicate the group of trunks containing the selected trunk and the location of the selected trunk in such group.

2. In a telephone exchange system, an operator's position, a plurality of trunks arranged in groups at said position, means at the operator's position for extending telephone connections over said trunks, trunk selecting switches, one for each group of trunks, means for operating said switches to select a trunk in any of said groups, indicator devices for indicating the group containing the selected trunk and the location of such trunk in the group, indicator selecting means for selecting said indicator devices, and means dependent on which trunk selecting switch is taken for use for determining the extent of operation of said indicator selecting means.

20 3. In a telephone exchange system, an operator's position, a plurality of trunks arranged in groups at said position, means controlled by the operator for extending telephone connections over said trunks, trunk selecting switches, one for each group of trunks, means for operating said switches to automatically select a trunk in any of said groups, indicator devices for indicating to the operator the designation of the group 25 containing the selected trunk and the designation of the selected trunk in such group, variably operable indicator selecting means for selecting said indicator devices, and means dependent on which one of said 30 trunks selecting switches is taken for use for determining the extent of operation of said indicator selecting means.

40 4. In a telephone exchange system, an operator's position, a plurality of trunks arranged in groups at said position, means controlled by the operator for extending telephone connections over said trunks, trunk selecting switches, one for each group of trunks, means for operating said switches to automatically select a trunk in any of said groups, indicator devices for indicating to the operator the designation of the group containing the selected trunk and the designation of the selected trunk in such group, variably operable indicator selecting means for selecting said indicator devices, and means dependent on which one of said trunk selecting switches is taken for use, and on the operation of such switch, for determining the extent of operation of said indicator selecting means.

5. In a telephone exchange system, an operator's position, a plurality of trunks arranged in groups at said position, means controlled by the operator for extending telephone connections over said trunks, trunk selecting switches, one for each group of trunks, means for operating said switches to automatically select an idle trunk in one of

said groups, means for rendering the selected trunk busy, indicator devices for indicating to the operator the designation of the group containing the selected trunk and the designation of the selected trunk, in such group, variably operable indicator selecting means for selecting said indicator devices and means dependent on which one of said trunk selecting switches is taken for use for determining the extent of operation of said indicator means. 65

6. In a telephone exchange system, an operator's position, a plurality of trunks arranged in groups at said position, means at said position for extending telephone connections over said trunks, trunk selecting switches, one for each group of trunks, means for operating said switches in succession to automatically select an idle trunk, indicator devices for indicating the designation of the group containing the selected trunk and the designation of the selected trunk in the group, variably operable indicator selecting means for selecting said indicator devices, and means dependent on which one of said trunk selecting switches is taken for use for determining the extent of operation of said indicator selecting means, 80 85 90

7. In a telephone exchange system, an operator's position, a plurality of trunks arranged in groups at said position, means at said position for extending telephone connections over said trunks, a series of trunk switches one for each group of trunks, means for operating said switches in succession to automatically select a group containing an idle trunk and to select the idle trunk in such group, indicator devices for indicating the designation of the selected group and the designation of the selected trunk in the group, variably operable indicator selecting means for selecting said devices, and means dependent on which one of said trunk selecting switches is taken for use and on the operation of such switch for determining the extent of operation of said indicator selecting means.

8. In a telephone exchange system, an operator's position, a plurality of trunks arranged in groups at said position, a series of trunk switches, one for each group of trunks, means for operating any one of said switches and a variable number of succeeding switches to automatically select a group containing an idle trunk and to select an idle trunk in such group, indicator devices for indicating the designation of the selected group and the designation of the selected trunk in the group, variably operable indicator selecting means for selecting said devices, and means dependent on which one of said trunk selecting switches is taken for use and on the operation of such switch for determining the

extent of operation of said indicator selecting means.

9. In a telephone exchange system, telephone lines, an operator's position, a plurality of trunks arranged in groups at said position, means for connecting the telephone lines to said trunks, automatic switches for extending said trunks, trunk switches, one for each group of trunks, means for operating said trunk switches to select an idle trunk, indicator devices for indicating the group containing the selected trunk and the location of the trunk in such group, variably operable indicator selecting means for selecting said indicator devices, means dependent on which trunk switch is taken for use for determining the extent of operation of said indicator selecting means, and means controlled by the operator for controlling the operation of said automatic switches.

10. In a telephone exchange system, telephone lines, an operator's position, a plurality of trunks arranged in groups at said position, means for connecting the telephone lines to said trunks, automatic switches for extending said trunks, trunk switches, one for each group of trunks, means for operating said trunk switches to select an idle trunk, indicator devices for indicating the group containing the selected trunk and the location of the trunk in such group, variably operable indicator selecting means for selecting said indicator devices, means dependent on which trunk switch is taken for use for determining the extent of operation of said indicator selecting means, and means controlled by the operator for controlling the operation of said automatic switches over the selected trunk.

11. In a telephone exchange system, an operator's position, a plurality of trunks arranged in groups at said position, trunk switches, one for each group of trunks, means for operating said switches to select an idle trunk, indicator devices for indicating the designation of the group containing the selected trunk, a variably operable indicator selecting switch for selecting said devices, and means dependent on which one of said trunk switches is taken for use

for determining the extent of operation of said indicator selecting switch.

12. In a telephone exchange system, an operator's position, a plurality of trunks arranged in groups at said position, trunk switches, one for each group of trunks, means for operating said switches to select an idle trunk, indicator lamps for indicating the designation of the group containing the selected trunk, a variably operable step-by-step switch for selecting said lamps, and means dependent on which one of said trunk switches is taken for use for determining the operation of said step-by-step switch.

13. In a telephone exchange system, an operator's position, a plurality of trunks arranged in groups at said position, trunk switches, one for each group of trunks, means for operating said switches to select an idle trunk, an auxiliary switch for controlling the operation of said trunk switches, means for positioning the auxiliary switch in accordance with which one of said trunk switches is taken for use, indicator devices for indicating the designation of the selected trunk, a variably operable indicator selecting switch for selecting said devices, and means dependent upon the position taken by said auxiliary switch for determining the operation of said indicator selecting switch.

14. In a telephone exchange system, an operator's position, a plurality of trunks arranged in groups at said position, trunk switches, one for each group of trunks, means for operating said switches to select an idle trunk, indicator devices for indicating the designation of the trunk groups, an indicator selecting switch for selecting said devices, means dependent on which one of said trunk switches is engaged for use for determining the operation of said selecting switch, other indicator devices for indicating the designation of the trunks in a group, a second selecting switch for selecting said last named devices, and means dependent on the operation of the trunk switch engaged for use for determining the operation of said second selecting switch.

In witness whereof, I hereunto subscribe my name this 12th day of May, A. D. 1920.

EDGAR H. CLARK.
